UNITED STATES PATENT OFFICE.

WARREN S. JOHNSON, OF MILWAUKEE, WISCONSIN.

AUTOMATIC PRESSURE-REGULATING VALVE.

SPECIFICATION forming part of Letters Patent No. 397,805, dated February 12, 1889.

Application filed October 31, 1888. Serial No. 289,667. (No model.)

To all whom it may concern:

Be it known that I, WARREN S. JOHNSON, of Milwaukee, in the county of Milwaukee and State of Wisconsin, have invented certain Improvements in Automatic Pressure-Regulating Valves, of which the following is a specification.

My invention relates to those automatic valves which are used for regulating or reducing the pressure of fluids delivered through them.

The object of the invention is to provide a valve which shall be at once simple, sensitive, and reliable.

To this end it consists in the combination of a tubular balanced valve and a diaphragm in the peculiar form and manner hereinafter described and claimed.

In the accompanying drawings, Figure 1 is a vertical axial section through a regulator constructed on my plan. Fig. 2 is a vertical axial section through the valve proper, showing also its supporting-spindle. Fig. 3 is a bottom plan view of the parts represented in Fig. 2.

Referring to the drawings, A represents the valve-body, having the inlet-throat *a* and outlet-throat *b*, separated by the intermediate septum, *c*, as usual. The body is provided with two vertical valve seats or throats, *d* and *e*, the former through the septum for the passage of the fluid and the latter through the top of the body.

B is the vertically-moving valve, having the two cylindrical or piston-like ends and a reduced central portion with guiding-ribs thereon, as usual. Its upper end is fitted within and constantly closes the upper seat or throat, *e*, while its lower end, of the same diameter, rises and falls through the lower seat or throat, *d*, to open and close the same, and thereby controlling the passage of fluid through the body.

The valve constructed as shown is subject when closed to equal pressures in upward and downward directions from the inflowing fluid, as in the familiar balanced valves of this type. Instead of making the valve *B* solid, as usual; I make it of a tubular form, (shown in Fig. 2,) or, in other words, with an opening centrally through it from end to end, so that

the fluid in the body at its delivery side may pass upward through the center of the valve into a top chamber, *C*, to act upon the diaphragm *D*, from which the valve is suspended. The construction of the chamber *C* and the details of the connections between the diaphragm and valve are not of the essence of the invention, and may be modified. I prefer, however, the construction shown in the drawings, in which the valve is connected at its lower end by a gimbal-joint, *f*, or other universal joint to the central spindle, *g*, which is extended upward through the valve and adjustably secured into a nut, *h*, fixed to the center of the diaphragm, so that the valve may be raised or lowered in relation to the diaphragm. A jam-nut, *i*, on the spindle *h* serves to lock it in position and prevent its accidental movement. The diaphragm, of rubber or similar flexible material, is contained at its edges between the upper and lower cap-like parts *c c*, which are secured together, and which jointly form the chamber *C*. The lower member, *c*, is formed with a central tubular neck, which is secured fast into a neck on the body *A*.

If the valve is to be adjustable to work under different pressures, I attach to the diaphragm, either through the nut *h* or otherwise, an upright spindle, *k*, and mount thereon a spiral spring, *l*, which is in turn seated within and compressed by a tubular screw, *m*, threaded into the top of the chamber *C*, and provided at its outer end with a hand-wheel, by which it may be adjusted in order to cause the spring to exert more or less downward pressure on the diaphragm. The upper end of the spindle may be guided by a screw in the central hole in the hand-wheel, as shown.

The fluid to be regulated passes into the valve-body through the throat *a* and escapes through the throat *b*.

It will be observed that when the valve is closed the pressure thereon is balanced or equalized in all directions, and that there is no tendency of the pressure upon the valve to either open or close the same. Owing, however, to the back-pressure of the fluid in the delivery side of the body, which has already passed the valve, it rises centrally through the valve proper into the chamber *C* and acts

against the under side of the diaphragm. As long as the proper pressure is maintained at the delivery side of the valve, the diaphragm holds the valve proper in its closed position. 5 Whenever the pressure at the delivery side falls below the predetermined limit, so as to lessen the pressure on the under side of the diaphragm, the valve, either by its gravity alone, or by its gravity supplemented by the 10 downward pressure of the spring, descends and opens the throat *d*, permitting the fluid to flow through the body from the inlet-port.

By adjusting the tension of the spring the valve may be caused to maintain any desired 15 pressure at the delivery side. When my valve is used for controlling steam-pressure, any water resulting from condensation in the chamber *C* can escape downward through the interior of the valve *B* into the lower part of 20 the body, from which it may be drawn in any suitable manner.

The connection of the valve to its spindle by a universal joint prevents it from binding in its seats in the event of the spindle or the 25 other connecting parts being out of line.

The adjustability of the valve *B* in relation to the controlling-diaphragm is of advantage in that it admits of the valve being adjusted to open to a greater or less extent, and also of 30 its being raised to compensate for the sagging of the diaphragm, as required.

In practice I find that in operating a regulator under light pressures and where extremely delicate regulations are demanded, it 35 is advantageous to use the valve of tubular form adapted to open the lower throat but keep the upper throat constantly closed, so that the inflowing fluid is compelled to pursue an intricate and retrograde course before

reaching the diaphragm. It is to be observed 40 that in my valve the upper throat, *e*, leads from the receiving side of the valve-body directly outward through its top into the diaphragm-chamber, so that the upper end of the valve proper is subjected to the pressure 45 of the fluid in said chamber.

Having thus described my invention, what I claim is—

1. The valve-body having the throat *d* for the passage of the fluid therethrough, and 50 also an independent throat, *e*, leading from the inlet side directly to the outside of the body, the diaphragm-chamber communicating with the throat *e* on the outside of the body, the diaphragm, the valve having its upper 55 end adapted to constantly close the throat *e* and its lower end adapted to open and close throat *d*, and having also a passage through its interior from the delivery side of the valve-body to the diaphragm-chamber, and a stem 60 connecting the valve and diaphragm, said parts combined for joint operation, as described and shown.

2. The body, the balanced tubular valve applied, as described and shown, the dia- 65 phragm-chamber, and the diaphragm, in combination with the adjustable screw-connection to change the relations of the diaphragm and valve, and the independent adjustable spring to depress the diaphragm. 70

In testimony whereof I hereunto set my hand, this 19th day of October, 1888, in the presence of two attesting witnesses.

WARREN S. JOHNSON.
